UNITED STATES PATENT OFFICE.

HARRY S. WILLIS, OF PHILADELPHIA, PENNSYLVANIA.

SHOE HEEL AND CUSHION PLUG THEREFOR.

Application filed August 21, 1923. Serial No. 658,526.

To all whom it may concern:

Be it known that I, HARRY S. WILLIS, a citizen of the United States, residing in Philadelphia, in the county of Philadelphia and State of Pennsylvania, have invented 5 new and useful Improvements in Shoe Heels and Cushion Plugs Therefor, of which the following is a specification.

My invention relates to a new and useful 10 improvement in shoe heel and cushion plugs therefor, and has for its object to so construct a heel that it may be readily and securely fastened to the shoe or a portion of the heel already secured to the shoe and provide 15 for detachably inserting cushion plugs in the completed heel in such manner as to lock said plugs against accidental displacement and yet provide for their removal for changing their locations, or substituting new 20 plugs for worn plugs.

With these and other ends in view, this invention consists in the details of construction and combination of elements hereinafter set forth and then specifically designated by 25 the claim.

In order that those skilled in the art to which this invention appertains, may understand how to make and use the same, I will describe its construction in detail, referring 30 by numerals to the accompanying drawing forming a part of this application, in which:—

Fig. 1, is a bottom plan view of a heel made in accordance with my invention showing 35 the cushion plugs therein.

Fig. 2, is a reverse view of the heel showing the arrangement of the air cells for giving the heel increased resiliency and a suction grip when secured in place; the threaded 40 holes for the plugs being omitted.

Fig. 3, is a section at the line 3—3 of Fig. 2.

Fig. 4, is a detail section of one of the 45 plugs.

In carrying out my invention as here embodied, I provide what is termed a rubber heel 1, which has its upper surface so moulded as to form the cells 2 produced by the

cross ribs 3 and the relatively sharp edge 4 the latter extending around the contour of 50 the heel, while the cross ribs extend diagonally across said heel as clearly shown in Fig. 2, a series of threaded holes 5 are formed through the rubber heel 1, and an annular recess 6 is formed in the outer face of this 55 heel around each of the threaded holes for the purpose herein set forth.

7 represents the threaded cushion plugs each of which has formed therewith an enlarged head 8 beneath the shoulder of which 60 is formed a groove 9 thereby producing the annular wedged shaped flange 10. When the plugs are screwed into the threaded holes 5 the flange 10 of each plug will pass within its respective recess 6, thus sealing the air 65 within the groove 9 so as to produce a pneumatic effect at this point which not only gives a greater resiliency to the plug, but serves to lock or hold the plug against rotation when the weight of the wearer of the 70 heel is upon the plugs.

In practice I have found this to be of great utility since any slight rotation of the heel when in contact with the pavement has a tendency to back the plugs out of their 75 threaded holes, but the pneumatic effect of the air sealed within the grooves 9 tends to force the flanges 10 outward binding them against the side walls of the recesses.

Of course I do not wish to be limited to 80 the exact details of construction as herein shown as these may be varied within the limits of the appended claim without departing from the spirit of my invention.

Having thus fully described my invention, 85 what I claim as new and useful is:—

A shoe heel having threaded holes each terminating in a recess at one end and threaded rubber plugs in said holes, each plug having a head provided with a groove 90 and flange, said flange engaging the inner surface of the recess to produce a frictional resistance against turning.

In testimony whereof, I have hereunto affixed my signature.

HARRY S. WILLIS.
